UNITED STATES PATENT OFFICE.

ERNST SALZMANN, OF SOLOTHURN, SWITZERLAND.

INKSTAND.

1,424,216.

Specification of Letters Patent. Patented Aug. 1, 1922.

Application filed August 10, 1920. Serial No. 402,675.

To all whom it may concern:

Be it known that I, ERNST SALZMANN, a citizen of Switzerland, and residing at Solothurn, Canton of Solothurn, have invented certain new and useful Improvements in Inkstands, of which the following is a specification.

The inkstands hitherto in use by draughtsmen for preserving liquid china ink had the disadvantage that whenever some ink had been withdrawn the stopper had to be taken off and had to be put on again in order to avoid the risk of having the contents of the inkstand vaporized and dried up and in case of upsetting the inkstand of having its contents spilled over the drawing. All these facts involved great trouble for the draughtsman, besides the irksome necessity, that for filling the drawing pen a goose quill or its equivalent had to be dipped several times into the inkstand and this the more, when the inkstand was nearly getting emptied.

Some of the inkstands hitherto known present likewise the disadvantage, that for filling the pen, especially, if the inkstand has not been kept filled up properly, the same repeated movement of dipping the pen will be needed, so that the ink inside of the stand is in almost constant open communication with the outside air. Besides the fine tubes through which the ink is to be withdrawn would inevitably get choked owing to the drying up of the ink.

By this present invention all these troubles will be overcome.

The object of the invention is an airtightly shut up inkstand permitting the filling of pens with china ink or ordinary ink without removing the stopper by simply depressing a knob. In the annexed drawing one working form of the invention is represented.

Fig. 1 is a central section thereof partly in view and

Fig. 2 a detail part.

A receptacle *a* for the ink is supported by a pedestal *b* the foot plate *c* of which is shaped like a saucer so as to receive any liquid dribbling from the receptacle. The receptacle is also provided with an opening closed by a screw cap *d* with an inlaid packing washer *d'* so as to permit of an air tight closing, which cap will not be liable of getting loose like an ordinary cork stopper. When removing the screw cap *d* the ink-

stand may therefore also be used like an ordinary inkstand where the pen is dipped in directly.

There are also two valve seats arranged one above the other the one in the top and the other in the bottom wall of the receptacle the corresponding valves *f* and *e* being provided on one and the same valve rod *g* which is ending in a slender conical point *m* which is projecting from out a conical neck *n* formed on the outside of the bottom wall. The lower valve *e* consists of a piece of rubber hose *q* sleeved over a spherical swelling *r* on the rod above its point *m* and the upper valve *f* is formed of a rubber or leather washer, kept adjustably fast between two small nuts on a threaded part of rod *g*. By this arrangement both valves may be brought to a simultaneous fit on their seats and the rubber hose as well as the washer may be easily replaced owing to the fact that rod *g* can be easily withdrawn from the receptacle by pulling out the pivot pin *h* of a lever *i* hinged to said rod. The tight cut-off of the liquid at the lower valve *e* is effected by the rubber on the spherical swelling, besides only a small play is left between the slender point *m* and the mouth of the conical neck.

This valve arrangement is one of the main features of the invention. Lever *i* swings on a pivot block secured to the stop side of the receptacle and a screw *l* provided with a milled knob is carried by said lever *i* which screw by way of adjustment is adapted to limit the play of lever *i* and thereby also the amount of opening of the valves. A helical spring *k* sleeved on said screw *l* and acting against the bottom side of lever *i* is adapted to keep the valves *e*, *f* pressed down on their seats. This spring *k* likewise like the valve packings *e* and *f* may be easily replaced by pulling out the pin *h* of lever *i*. If only a small play is left between the end of screw *l* and receptacle *a* and when the knob *o* is pressed down, the valves will be opened only to a small amount and then only a small quantity of ink will appear at the point of cone *m*, but if a large play is left, a large drop of ink will appear at the point of *m*. If however screwed down firmly lever *i* will be blocked keeping valves *e*, *f* tightly shut. This latter position will correspond therefore to the position for transport and of rest as any risk of leakage through the valves is rendered impossible. The outlet of the liquid through the lower valve *e* is

- warranted by the simultaneous opening of the upper valve *f*, whenever the knob of screw *l* has been pressed down, because any loss of liquid, through the lower valve will be compensated at once by the inlet of air through the upper valve. The outlet of liquid will last as long as the pressure on the knob. In most cases a short touch of the knob will be sufficient. As the valve *e* is located at the bottom of the receptacle all the ink may be withdrawn to its last drop. Any crust of dried ink formed at the outlet of the neck will be removed with safety whenever cone *m* is moved; so that an unobstructed working of the inkstand will be obtained.
- In the bottom wall of the receptacle a central excavation *p* is provided where all impurities contained in the liquid may collect.
- In order to facilitate the simultaneous use of inkstands containing inks of different colours the knob of screw *l* may be fitted with a coloured plate *o* having the same colour as the liquid contained within the inkstand.

I am well aware that it is not new to build inkstands with an air tightly shut receptacle and two valves on the same valve rod simultaneously operated by pressing on a knob of a lever connected to said rod and that it is not new to have the outlet valve conically shaped but having a flat washer for tightening. Such valves however have not proved to work satisfactory.

The new outlet valve is constructed like a needle valve and the resilient rubber hose assures an exact adjustment of the outlet opening so as to work at entire satisfaction.

What I claim, is:

In an inkstand comprising an air tight receptacle having a needle valve outlet operated by a hand lever the combination with the conical outlet neck *n* of the valve, a valve rod *g* provided with a spherical swelling *r* and a rubber hose *q* sleeved over said swelling for the purpose set forth and substantially as shown and described.

In testimony whereof I affix my signature.

ERNST SALZMANN.
